UNITED STATES PATENT OFFICE.

CHARLES E. PHILLIPS, OF CLEVELAND, OHIO.

DESIGN FOR A TOBACCO PIPE.

Application filed September 18, 1925. Serial No. 14,817. Term of patent 3½ years.

To all whom it may concern:

Be it known that I, CHARLES E. PHILLIPS, a citizen of the United States, residing at Cleveland, in the county of Cuyahoga and State of Ohio, have invented a new, original, and ornamental Design for Tobacco Pipes, of which the following is a specification, reference being had to the accompanying drawing, forming a part thereof, in which the figure is a side elevation of the article, showing my new design.

I claim:

The ornamental design for a tobacco pipe as shown.

CHARLES E. PHILLIPS.
